U.S. Cl. D66—1

FIG. 1

FIG. 2

FIG 5

FIG. 1 is a front elevational view of a guideway following vehicle showing our new design, it being understood that the broken lines are for illustrative purposes only;

FIG. 2 is a right side elevational view thereof;

FIG. 3 is a left side elevational view thereof;

FIG. 4 is a top plan view thereof;

FIG. 5 is a perspective view showing the rear, left side and top of a guideway following vehicle showing a second embodiment of our new design; and

FIG. 6 is a perspective view showing the rear, right side and top thereof.

The undisclosed rear of the guideway following vehicle shown in FIGS. 1-4 is substantially a mirror image of the front shown in FIG. 1; and the undisclosed front of the guideway following vehicle shown in FIGS. 5 and 6 is substantially a mirror image of the rear shown therein.

We claim:

The ornamental design for a guideway following vehicle, substantially as shown and described.
